[57] CLAIM

The ornamental design for a vehicle tire, substantially as shown and described.

DESCRIPTION

FIG. 1 is a perspective view of a vehicle tire showing our new design, it being understood that the tread design is repeated throughout the circumference of the tire, the opposite side being the same as that shown; FIG. 2 is a side elevational view thereof; FIG. 3 is a front elevational view thereof; FIG. 4 is an enlarged fragmentary plan view showing the tread design thereof; and FIG. 5 is a cross sectional view thereof taken along the line V—V of FIG. 3.
